COMBINATION ILLUMINATED VANITY CASE
AND UTILITY LIGHT

Charles F. Scott, Mina, Nev.

Application July 31, 1947, Serial No. 765,067

2 Claims. (Cl. 240—6.45)

1

This invention relates to new and useful improvements in vanity cases and more particularly to illuminated vanity cases.

The primary object of the present invention is to provide a vanity case including an electrical lamp for reflecting the light of said lamp upon the face of the user of the case while looking into the mirror when the cover therefor is in a raised or open position.

Another important object of the present invention is to provide a vanity case embodying novel and improved switch means actuating a circuit for energizing a lamp.

A further object of the present invention is to provide a vanity case including an insert having rouge and powder chambers and side walls that retain the battery shells for the electrical lamp in a fixed position within the case.

A still further aim of the present invention is to provide a vanity case that is simple and practical in construction, neat and attractive in appearance, strong and reliable in use, relatively inexpensive to manufacture, and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view of the vanity case constructed in accordance with the present invention, and showing the cover therefor in an open position;

Figure 2 is a fragmentary top plan view of the vanity case with parts of the cover broken away and shown in section, and with the inserts removed from the casing;

Figure 3 is a transverse vertical sectional view of the vanity case showing the cover therefor in a closed position;

Figure 4 is a longitudinal vertical sectional view of the vanity case showing the cover therefor in a closed position; and

Figure 5 is a fragmentary top plan view of the forward portion of the casing with parts broken away and shown in section.

Referring now to the drawings in detail, where in for the purpose of illustration, there is disclosed a preferred embodiment of the present invention, the numeral 10 represents a casing generally comprising a substantially flat trapezoidal sheet of any suitable material 12 having its side

2

edges turned upwardly to provide flanged portions 14.

Hinged at one edge to the rear flange portion of the casing, is a substantially trapezoidal cover 16 having a mirror 18 recessed in the inner face of the cover and suitably secured thereto.

Projecting outwardly from the forward end of the cover at its inner face, is a pin or lug 20 that engages an aperture 22 provided in the forward flanged portion of the casing. A notch is provided in the lug to form a lip 24 at the outer end of the lug, that extends through an aperture in a resilient clip 26 extending through an aperture in the forward flanged portion of the casing and having its inner end suitably secured to the inner face of the flanged forward portion of the case.

The lug bears against the underside of the clip 26 for holding the cover in a closed position on the casing.

An aperture 28 is centrally disposed in the forward flanged portion of the casing and receives a sleeve 30 supporting the base portion of an electrical lamp 32, with the enlarged head portion of the lamp recessed in an enlarged opening 34 provided in the forward flanged portion of the casing surrounding aperture 28.

Projecting inwardly from the side flanged portions of the casing near the rear end thereof, is a pair of resilient contact clips 36 and 38, also projecting inwardly from the side flanged portions of the casing near the forward end thereof, is a second pair of resilient contact clips 40 and 42. Clips 36 and 40 engage a battery cell 44 with the terminal of the cell bearing against clip 40 and clips 38 and 42 engage a second battery cell 45 with its terminal bearing against clip 38.

The clips 36 and 38 are connected by an electrical wire 46 and clip 40 is connected to sleeve 30 by a further electrical wire 48.

Fixedly secured to the casing near the forward end thereof, is a metallic plate 50 having a right angular extension 52 turned outwardly to bear against the terminal of lamp 32. Pivotally mounted on plate 50 is a substantially V-shaped switch bar 54 having one of its terminal portions turned outwardly as at 55 to selectively engage a resilient finger 56 carried by clip 52, and the opposite terminal portion of the bar 54 extends through a slot in the casing and is provided with a finger gripping knob 58 recessed in a groove 60 provided in the forward flanged portion of the casing.

The numeral 62 represents generally a substantially box-like insert for the casing. This insert includes a transverse partition 64 dividing

the insert into a powder chamber 66 and a rouge chamber 68. The longitudinal side walls 74 of the insert bear against the battery cells preventing movement of the cells within the casing, as shown best in Figure 3 of the drawings. The outer edges of the insert are integrally formed with a substantially trapezoidal peripheral flanged portion 76, the free edges of which engage a peripheral shoulder 78 provided about the flanged portions 14 of the casing, whereby the outer face of the peripheral flange 78 will be in a similar plane with the outer extremities of the flanged portions 14.

Obviously, from the foregoing structure, by pushing knob 58 in one direction the circuit between the battery cells and lamp is completed and the lamp will be energized. By pushing the knob 58 in an opposite direction, bar 54 disengages finger 56 and the circuit is open and the lamp is not energized. Since no part of the actuating or switch bar 54 projects outwardly of the casing it will be difficult for the circuit to be accidentally closed when the device is being carried in a handbag or the like.

The cover being in a closed position to the casing, it is merely necessary to push inwardly of the outwardly projecting end of clip 26, which disengages lip 24 with the plate 26. When inward pressure is released from the clip 26, the same will return to its normal aforesaid position to engage the lug 24 when the cover is closed again.

In view of the foregoing description taken in conjunction with the accompanying drawings it is believed that a clear understanding of the construction, operation and advantages of the device will be quite apparent to those skilled in this art. A more detailed description is accordingly deemed unnecessary.

It is to be understood, however, that even though there is herein shown and described a preferred embodiment of the invention the same is susceptible to certain changes fully comprehended by the spirit of the invention as herein described and the scope of the appended claims.

Having described the invention what is claimed as new is:

1. A vanity case comprising an elongated casing having a forward tapered end, a cover hinged to said casing, means for locking said cover in a closed position to said casing, a mirror on the

inner face of said cover, a pair of spaced parallel oppositely arranged battery cells removably carried within said casing at opposite sides thereof, resilient contact clips carried by said casing supporting said battery cells, a conductor between one end of each of said battery cells, the tapered end of said casing having an aperture in its apex, a sleeve positioned in the aperture and disposed longitudinally of said case, a circuit between said sleeve and one of said battery cells, an electric lamp carried by said sleeve, the head portion of said lamp being recessed in said casing, a contact plate secured to said casing disposed at the tapered end of the casing and having one end turned outwardly to engage the terminal of said lamp, a bell crank lever switch pivotally mounted on said plate, a contact finger carried by one of said battery cells engaging said switch for completing a circuit between said battery cells and said lamp, and a finger gripping knob carried by said switch for actuating said switch.

2. An illuminating attachment for vanity cases comprising first and second batteries, each of said batteries including a base portion and a terminal, a conductor connecting the base portion of said first battery to the terminal of said second battery, a lamp socket, a further conductor connecting said lamp socket to the terminal of said first battery, a lamp carried by said socket and including a terminal, a still further conductor engaging the terminal of said lamp, a contact finger connected to the base portion of said second battery, and a bell crank lever switch pivoted on said still further conductor for engaging said finger.

CHARLES F. SCOTT.
